Specification for Design.

Patented Dec. 14, 1920.

Application filed June 30, 1920. Serial No. 393,182. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for a Chandelier-Body Plate for a Lighting-Fixture, of which the following is a specification, reference being had to the accompanying drawings, forming part thereof.

Figures 1 and 2 of the accompanying

drawings are respectively plan and cross-sectional views of a chandelier body plate for a lighting fixture, showing our new design. The surface ornamentation is shown only upon a portion of the plan view; it being understood that the surface ornamentation shown is repeated over the entire surface.

We claim:

The ornamental design for a chandelier body plate for a lighting fixture, as shown.

GEORGE V. STRAHAN.
